Merchant and Kilroe

UNITED STATES PATENT OFFICE.

WALTER SANDS, OF MINNEAPOLIS, MINNESOTA.

DETACHABLE MOP WRINGER.

Application filed June 9, 1927. Serial No. 197,567.

My present invention has for its object to provide an extremely simple and highly efficient detachable mop wringer, and to this end it consists of the novel devices and combinations of devices hereinafter described and defined in the claims.

Said mop wringer is designed for application to an ordinary galvanized pail without the use of movable or adjustable fastening devices, and when not in use may be easily removed from the pail and hung up out of the way. By detachably applying the mop wringer to a pail, the same, together with said pail, may be easily kept clean and in sanitary condition.

In the accompanying drawings, which illustrate the invention, like characters indicate like parts throughout the several views.

Referring to the drawings:

Fig. 1 is a perspective view of the mop wringer with a part indicated in different positions by means of broken lines;

Fig. 2 is a view principally in central vertical section showing the mop wringer applied to a pail and also showing a mop head and mop;

Fig. 3 is a transverse section taken on the line 3—3 of Fig. 2, on an enlarged scale; and

Fig. 4 is a fragmentary detail view with some parts sectioned on the line 4—4 of Fig. 3.

The numeral 5 indicates an ordinary galvanized pail having an outwardly rolled rim 6.

The improved mop wringer includes a U-shaped main frame adapted to span the top of the pail 5 and rest on its rim 6. The transverse portion of the main frame 7, at its intermediate portion, is outwardly bowed at 8 to substantially the same curvature as the rim 6, and has integrally formed therewith a pair of circumferentially spaced inner jaws 9 and an integrally formed outer jaw 10 located midway between said inner jaws. Said jaws 9 and 10 are in the form of relatively wide flat lugs bowed away from each other so that their free edges afford biting surfaces and also to cause the jaw 10 to clear the rim 6. It will be noted that the biting surfaces of the jaws 9 and 10 are spaced to afford an entrance gap with sufficient clearance for the bead 6, and it is also important to note that the biting surface of

the jaw 10 is located above the biting surfaces of the jaws 9.

To apply the mop wringer to the pail 5, the main frame 7 is held in an oblique position over the top of the pail 5 to pass the jaws 9 and 10 transversely over the rim 6. Said main frame 7 is then moved in a hinge-like manner toward the top of the pail 5, and the biting surfaces of the jaws 9 and 10 are so arranged as to engage, respectively, the inner and outer sides of the pail 5 before the main frame 7 is in a horizontal position, thus requiring slight pressure to complete the movement of the main frame 7 onto the top of the pail 5 which causes the jaws 9 and 10 to bite onto opposite sides of the pail 5 and thereby securely attaches the mop wringer to the pail 5.

As the jaws 9 and 10 alternately engage the inner and outer sides of the pail 5 at circumferentially spaced points, a three-point contact is secured between the main frame 7 and the pail 5. This connection between the main frame 7 and the pail 5 securely locks the mop wringer to the pail 5 and holds the same against lateral angular movement on said pail.

A lower roll 11 is journaled between and to the sides of the main frame 7 with its axis parallel to the transverse portion of said main frame and located relatively close thereto.

A secondary U-shaped frame 12 has its arms pivoted to and between the sides of the main frame 7, as indicated at 13. An upper roll 14 is journaled to and between the arms of the secondary frame 12, near the free ends thereof, for co-operation with the lower roll 11. A foot pressure plate 15 is applied to the arms of the secondary frame 12 just rearward of the roll 14. This foot plate 15 rests on the upper edges of the arms of the secondary frame 12 and its end portions are folded outward and around said arms, as indicated at 16, to rigidly secure said foot plate to the secondary frame 12.

The longitudinal edge portions of the pressure plate 15 are bent downward between the arms of the secondary frame 12 to afford reinforcing flanges 17, the ends of which are engaged by said arms and hold the same parallel and laterally spaced.

To prevent the operator's foot from slip-

ping on the pressure plate 15, the rear half of said plate has pressed therefrom upstanding longitudinally extended parallel ribs 18 that progressively decrease in height toward the upper roll 14.

To prevent the secondary frame 12 from being turned into a position on the under side of the main frame 7 and thereby keep the same in its proper relation to the roll 10, the free end portions of the sides of the main frame 7 are bent laterally toward each other to afford a pair of stop lugs 19 arranged to be engaged by the arms of the secondary frame 12.

15 It will be noted by reference to Fig. 1 that the sides of the main frame 12, between the roll 11 and the pivots 13, are outwardly bowed at 20 to afford sufficient clearance therebetween to permit a mop *x* applied to 20 a mop head *y* to be freely dropped into the pail 5 between the rolls 11 and 14.

To tilt the secondary frame 12 and thereby move the upper roll 14 away from the lower roll 11 during the insertion of the 25 mop x into the pail 5 and the removal therefrom, a foot piece 21 is detachably and removably applied to the transverse portion of the secondary frame 12 and normally projects rearward therefrom, as indicated by 30 full lines in Figs. 1 and 2.

To detachably secure the foot piece 21 to the supplemental frame 12, the inner end portion of said plate is folded to form a clip 22 that fits over the transverse portion of 35 said frame with a spring action. The purpose of detachably applying the foot piece 21 to the secondary frame 12 is to permit said foot piece to be turned into a position, as indicated by dotted lines in Fig. 1, to 40 facilitate the shipping and packing of the mop wringer.

The location of the pressure plate 13 is such that a person may step thereon and apply sufficient pressure on the supplemental frame 12 to cause the rolls 11 and 14 to produce a wringing action on the mop π as the same is drawn between said rolls, and at the same time, this pressure, which is substantially at the center of the pail, securely holds the main frame 7 pressed onto the rim 6 of the pail 5 and also prevents said pail from tipping.

The above described mop wringer, while very light, is strong and durable and can be operated with very little effort on the part of the operator.

What I claim is:

60 1. A detachable mop wringer including a frame adapted to rest on a pail and having jaws with biting surfaces spaced both vertically and horizontally to afford an entrance gap for the rim of the pail and for engagement with the inner and outer faces of the pail for securing the frame thereto.

65 2. The structure defined in claim 1 in

which the jaw at the outer face of the pail is outwardly bowed to receive the rim of the pail.

3. A detachable mop wringer including a frame adapted to rest on a pail and having jaws with biting surfaces spaced both vertically and horizontally to afford an entrance gap for the rim of the pail and for alternate three-point contact with the inner and outer faces of the pail at circumferentially spaced points for securing the frame to the pail. 70 75

4. A mop wringer comprising a main frame applicable to a pail and having a lower roll journaled thereto, a secondary frame hinged to the main frame and including a pair of arms, an upper roll journaled to said arms for co-operation with the lower roll, a foot pressure plate applied to said arms, the longitudinal edge portions of said plate being turned down between said arms to afford reinforcing flanges, the ends of which are engaged by the arms to hold the same laterally spaced, the end portions of said plate being supported on the arms and folded outward therearound to attach said plate thereto and hold the arms against the ends of said flanges.

5. A mop wringer comprising a main U-shaped frame having jaws on its transverse portion applicable to a pail, a lower roll journaled to and between the sides of the main frame, a U-shaped secondary frame, the arms of which are pivoted to and between the sides of the main frame with the transverse portion of said secondary frame closing the gap between the sides of the main frame, an upper roll journaled to and between the arms of the secondary frame at the free end portions thereof for co-operation with the lower roll, a foot pressure plate on the secondary frame, and a foot piece applied to the transverse portion of the secondary frame.

6. A mop wringer comprising a main U-shaped frame having jaws on its transverse portion applicable to a pail, the end portions of the sides of said frame being turned toward each other to afford stop lugs, a lower roll journaled to and between the sides of the main frame, a U-shaped secondary frame, the arms of which are pivoted to and between the sides of the main frame with the transverse portion of said secondary frame closing the gap between the sides of the main frame, said stop lugs being arranged to be engaged by the arms of the secondary frame to limit the movement of the upper roll away from the lower roll, an upper roll journaled to and between the arms of the secondary frame at the free end portions thereof for co-operation with the lower roll, and a foot pressure plate on the secondary frame, said stop lugs being arranged to be engaged by the arms of the secondary frame

to prevent said secondary frame from being moved to the other side of the main frame.

7. The structure defined in claim 5 in which the foot piece is detachably applied to the transverse portion of the secondary frame whereby the same may be turned to project either into the secondary frame or out of the same.

8. A mop wringer comprising a main frame having a lower roll journaled thereon, a secondary frame hinged to the main frame and having an upper roll journaled thereto for co-operation with the lower roll, and a foot piece having a yoke-like clip adapted to be sprung onto a part of the secondary frame to detachably secure said foot piece thereto.

9. A detachable mop wringer including a frame, opposing jaws on the frame spaced to afford an entrance gap for the rim of the pail when said frame is held oblique to the top of the pail, said jaws being arranged to engage the inner and outer faces of the

pail with a clamping action produced by a hinge-like movement of the frame toward the top of the pail to lock the frame to the pail.

10. The structure defined in claim 9 in which the jaw arranged to engage the inner face of the pail is vertically spaced below the jaw arranged to engage the outer face thereof.

11. A detachable mop wringer including a frame adapted to rest on a pail, jaws on the frame having opposing biting surfaces spaced both vertically and horizontally to afford an entrance gap for the rim of the pail when said frame is held oblique to the top of the pail, said biting surfaces being arranged to engage the inner and outer faces of the pail with a clamping action produced by a hinge-like movement of the frame toward the top of the pail to lock the frame thereto.

In testimony whereof I affix my signature.
WALTER SANDS.
